(57) **CLAIM**

The ornamental design for a table as shown and described.

DESCRIPTION

FIG. 1 is a perspective view of a table showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area 9 shown in FIG. 1.

The broken lines depict portions of the table that form no part of the claimed design. The dash dot dash broken lines depict the cut line of the enlarged views and form no part of the claim.

1 Claim, 9 Drawing Sheets
